UNITED STATES PATENT OFFICE.

GEORGE CARROLL, OF NEW SALEM, ILLINOIS.

ROAD-DRAG.

1,179,608.

Specification of Letters Patent. Patented Apr. 18, 1916.

Application filed August 13, 1914. Serial No. 856,617.

To all whom it may concern:

Be it known that I, GEORGE CARROLL, a citizen of the United States, residing at New Salem, in the county of Pike and State of Illinois, have invented certain new and useful Improvements in Road-Drags, of which the following is a specification.

My invention relates to new and useful improvements in road-drags, and as its 10 principal object aims to provide an apparatus of this character which includes as its essential elements of construction a drag bar or board and a sharp edged scraper blade.

15 A further and more specific object of my invention is to provide a road-drag in which the scraper blade is mounted for swinging movement and is adapted to be adjusted to various angles of inclination with respect 20 to the road-bed by a centrally located manually operable lever.

A still further object of my present invention is to provide a novel form of fastening rods for holding the scraper blade in 25 adjusted position.

Another and more general object is to construct the apparatus with such regard to proportion and arrangement of parts that it may be cheaply manufactured, will be durable and efficient in its action and may be 30 readily adapted for use on roads of varying topography.

The above and other incidental objects of a similar nature, which will be herein- 35 after more specifically treated, are accomplished by such means as are illustrated in the accompanying drawings, described in the following specification, and then more particularly pointed out in the claim, which 40 is appended hereto and forms a part of this application.

Referring to the drawings, wherein there has been illustrated the preferred embodiment of this invention as it is reduced to 45 practice, and throughout the several views of which similar reference characters designate corresponding parts, Figure 1 is a top plan view; Fig. 2 is a vertical section illustrating the scraper blade in engagement 50 with the ground; Fig. 3 is a section similar to Fig. 2, illustrating the scraper blade raised to an inoperative position, and further showing the ground wheels in engagement with the ground.

55 The embodiment of my invention shown in the accompanying drawings includes as

the essential features of construction a drag bar or board 10, a scraper blade 11, an adjusting lever 12, which is manually operable from the approximate center of the 60 drag for varying the angle of inclination of the scraper blade to the road-bed, and a pair of holding bars 13 and 14 which are adapted to be secured by cam locks 15 and 16 for the purpose of securing the scraper 65 blade in adjusted position.

The drag bar 10 is in the preferred embodiment of the invention formed from a relatively heavy wooden plank, although, if so desired, a metal bar or plate may be employed. When a wooden plank is utilized, the lower edge thereof is rounded, as best shown in Figs. 2 and 3, and is provided with a metallic protecting shoe 17 which is substantially U-shaped in cross section and is 70 secured by bolts or other suitable fastening devices 18 in the proper position to embrace the rounded edge of the member 10. The upper edge of the member 10 is cut to extend at an angle to the forward face 19 so that, 75 when the frame members 20 are in normal horizontal position, the member 10 will extend at a rearward angle with respect to the road-bed. The purpose in thus arranging the drag bar so that it will bear 80 an angular relation to the road-bed at all times is to render the drag bar capable of 85 withstanding a maximum strain.

The frame members 20, by which the drag bar and scraper blade 11 are connected, are 90 preferably formed from metal bars, although, if so desired, wooden scantling may be employed. The rear terminals of these members 20 are rigidly secured, as by fastening devices 20', to the upper edge of the 95 member 10, while the forward terminals of the member 20 are pivotally secured to the scraper blade 11. For this latter purpose I employ an axle or shaft 21 which is freely 100 received in bearings 22 formed on the forward terminals of the members 20. It is now to be observed that one frame member 20 is provided for each terminal of the device, and that a pair of frame members, designated individually by the numerals 23 and 24, are disposed at the approximate center of the drag and in relatively close spaced relation to each other. The blade 11 is swingingly mounted on the axle 21 by means of attaching strips or plates 25, 110 which are apertured at their upper terminals to receive the axle and are rigidly secured

in vertical position against the rear face of the blade 11 by means of bolts or rivets, indicated at 26. It is now to be noted that the centrally located attaching strip 25 is disposed between the forward terminals of the members 23 and 24, while the terminally disposed members 25 are respectively disposed to bear against the inner faces of the terminally located bearings 22. It will thus 5 be seen that the blade is held against longitudinal movement on the axle during the use of the drag.

As has been previously explained, I employ a lever 12 as the means for accomplishing the angular adjustment of the scraper blade 11. The lever 12 is pivotally mounted on the axle 27 which is carried by a clutch plate 28 mounted on the centrally disposed frame member 24. This clutch plate is provided with conventional teeth 29 which are engageable by a spring-pressed pawl 30 which is associated with the lever 12 in the well-known manner. Connecting the lower terminal of the member 12 to the blade 11 is 15 the link 31, the lower terminal of which is received by a pin 32 passing through the lower apertured ear 33 of the centrally located attaching strip 25. It will be readily seen that by manipulating the lever 12, the blade 11 may be readily adjusted to the desired angular inclination to the road-bed.

The holding bars 13 and 14, which, as has been previously explained, are employed in securing the member 11 in adjusted position, 20 are preferably formed from metal bars, and are pivoted at their forward terminals to apertured ears 34 which are formed on the lower ends of the terminally located attaching strip 25. On the lower edge of the rear terminals of the bars 13 and 14 are formed the locking teeth 36 which are engageable in a manner shown in Fig. 2, with an under cut shoulder 37. A shoulder 37 is, as illustrated, formed adjacent each terminal of the member 10, and at the upper edge thereof by 25 forming notches 38 and 39. In order to prevent the disengagement of the teeth 36 when the holding bars 13 and 14 have been adjusted in the desired manner, I employ a pair of pivotally mounted cam locking members, heretofore designated by the numerals 15 and 16. These members 15 and 16 are formed in the nature of metal disks, and are pivoted intermediate their length by means 30 of a pin 40 carried by supporting brackets 41 which are secured to the upper edge portion of the member 10. The manner in which the members 15 and 16 may be engaged with the upper edges of the bars 13 and 14 for holding the teeth 36 in locking engagement with the shoulders 37 will be readily appreciated when reference is had to Fig. 2. A draft tongue of any conventional type, indicated by the numeral 42 may be 35 attached to the members 23 and 24.

In order that the scraper blade 11 may be lifted out of engagement with the ground, when the apparatus is being transported to or from the scene of operation, I provide a pair of wheels 43 and 44. These wheels 43 70 and 44 are journaled on stub axles 45 and 46 which are carried respectively by the enlarged lower terminals 47 and 48 of a pair of supporting legs or levers 49 and 50. These members 49 and 50 are pivoted intermediate their length on stub axles 51 which are carried by the members 13 and 14 adjacent their forward terminals. 75

It will be obvious, particularly when reference is had to Fig. 2, that the lever 50 may 80 be swung to such position that the cutting edge of the scraper blade 11 may engage in the desired manner with the road-bed. On the other hand, the levers 49 and 50 may be swung rearwardly so as to dispose the 85 wheels 44 and 45 in a lower plane, thereby lifting the scraper blade 11 out of engagement with the ground in the manner disclosed in Fig. 3. When the wheels are arranged as in Fig. 3, they make it possible for 90 the apparatus to be drawn along a road by a team of horses without imposing any unusual load upon the animals.

It will now be obvious that I have provided an unusually simple road-drag in 95 which the scraper blade works in advance of a relatively heavy drag bar. It will be apparent that when the road drag is in use, the blade 11 will first act to remove any uneven places in the road, and that following 100 the scraping action of the blade, the drag bar will act to pack down any dirt which may have been loosened by the scraper blade.

In reduction to practice, it has been found that the form of this invention illustrated in 105 the drawings, and referred to in the above description as the preferred embodiment, is the most efficient and practical; yet realizing that the conditions concurrent with the adoption of this device will necessarily vary, 110 it is desirable to emphasize the fact that various minor changes in details of construction, proportion and arrangement of parts may be resorted to, when required, without sacrificing any of the advantages of this invention, as defined in the appended claim. 115

Having thus described the invention, what I claim as new is:—

The improved road drag herein described and shown comprising longitudinal frame 120 bars, a drag bar secured rigidly to the rear ends of the frame bars and depending therefrom and inclined rearwardly with respect thereto, an axle secured in the front ends of the frame bars, a scraper, attaching strips 125 secured rigidly to the scraper and having their upper ends pivotally hung on the axle adjacent the frame bars whereby they are prevented from moving laterally, an adjusting lever mounted on a frame bar and de- 130

pending below the same, a link pivoted at its rear end to the lower end of said lever and at its front end to the lower end of an intermediate attaching strip, holding bars pivoted at their front ends to the lower ends of the attaching strip and extending rearwardly therefrom over and adjustably engaging the upper edge of the drag bar, and

means for locking said holding bars to the drag bar in an adjusted position. ¹⁰

In testimony whereof I affix my signature in presence of two witnesses.

GEORGE CARROLL. [L.S.]
